UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

ATTACHMENT FOR SEWING MACHINES.

1,420,414.

Specification of Letters Patent. Patented June 20, 1922.

Application filed October 29, 1919. Serial No. 334,139.

To all whom it may concern:

Be it known that I, ALBERT H. DE VOE, a citizen of the United States, residing at Westfield, in the county of Union and State 5 of New Jersey, have invented certain new and useful Improvements in Attachments for Sewing Machines, of which the following is a specification, reference being had therein to the accompanying drawings.

10 This invention relates to attachments for sewing machines and more particularly to a combined folding device and edge-guide.

The invention has for an object to provide an attachment capable of producing 15 folds of different widths and for guiding the edge of a fabric when a fold is not desired.

A further object of the invention is to construct a folding device in which the parts thereof may be retracted to inoperative positions to permit the completion of a fold 20 on tubular work.

The objects are attained in the present attachment which comprises a base-plate upon which are slidably mounted two supporting 25 plates one carrying a folding scroll and the other supporting a cooperating tongue about which the fabric is folded. An adjustable edge-guide is located beneath the folding tongue and projects above the surface of the 30 base-plate to guide the edge of the fabric. The folding scroll and folding tongue are each adjustable with respect to the edge-guide to either of two operative positions whereby folds of different widths are produced, it being understood that the width of 35 the fold is determined by the distance from the edge-guide to the edge of the folding tongue about which the fabric is folded. The folding scroll and tongue may be retracted in opposite directions to inoperative 40 positions when a fold is not desired or to permit the completion of a fold on tubular work.

The invention may be used advantageously in the manufacture of undershirts and will be described in connection therewith only as one product in which the advantages of the various adjustments may be utilized.

An embodiment of the invention is illustrated in the accompanying drawings in which Fig. 1 is a sectional elevation of a portion of a sewing machine upon which is fitted the present attachment adjusted to form a narrow fold. Fig. 2 is a plan view 55 of the parts shown in Fig. 1. Fig. 3 is a

view similar to Fig. 2 but showing the folding scroll and tongue adjusted to form a wide fold. Fig. 4 is a right end elevation of certain parts shown in Fig. 1. Fig. 5 is a sectional view taken on the line 5—5, Fig. 60 3, and Fig. 6 is a view of one product of the present invention.

Referring more particularly to the drawings, the attachment is shown as applied to a sewing machine provided with a cloth-plate 1, feeding mechanism 2, presser-foot *p* and stitch-forming mechanism comprising a plurality of needles 3 and a complementary looper 4, whereby a plurality of seams is formed on one side of a fabric and are connected on the opposite side of the fabric by a cross-thread as is commonly used to cover the raw edge of a folded fabric. The line of seam formation produced by the stitch-forming mechanism is represented by the 70 75 dot-dash lines *y* in Fig. 3.

The attachment is preferably formed with a base-plate 5 secured upon a slide-plate 6 adapted to be inserted within an attachment holder 7, carried by the cloth-plate 1, and held therein by a frictional engagement with a retaining spring 8. The base-plate 5 is formed with an undercut slideway 9 within which is slidably mounted the shank 10 of an edge-guide 11 adapted to determine the 85 position of the edge of the fabric with respect to the needles and held in adjusted positions by a set-screw 12 threaded through the shank 10 and bearing upon the surface 13 of the slideway 9. 90

An open sided folding scroll 14, provided with a shank 15, is also adjustably mounted within the slideway 9 and cooperates with a folding tongue 16 which projects into said folding scroll and which is adjustably 95 mounted upon the shank 10 of the edge-guide 11 and guided thereon by a down-turned lip 17, a block 16' carried by the under side of the folding tongue and a screw 18 projecting through a slot 19 in the tongue 100 16 and threaded into the shank 10 of the edge-guide. The folding scroll and folding tongue are maintained in adjusted positions by means of spring-latches 20 and 21, respectively, secured to the under side of the plate 105 5 and having portions 20' and 21', respectively, accessible from above the plate 5, the latch 20 cooperating with notches 20^a and 20^b formed in the shank of the folding scroll and the latch 21 cooperating with 110

notches 21^a and 21^b in the lip 17 of the folding tongue 16.

In the operation of the attachment when used for manufacturing undershirts the folding scroll and folding tongue are adjusted to the positions shown in Figs. 1 and 2 and a narrow fold is formed at the neck of the shirt *s* beginning at a point *b* at the front thereof and extending to a point *c*, 10 or until the reinforcing piece *r* is reached.

The folding scroll is then retracted to the position shown in dotted lines, Fig. 2, with the latch 20 engaging the notch 20^b. The edge *d* of the reinforcing piece *r* is then 15 guided by the edge-guide 11 and covering stitches are formed thereover attaching it to the body of the shirt until the point *e* is reached. During the stitching of the edge of the reinforcing piece the folding tongue 20 is maintained in its initial position and assists in holding down said reinforcing piece. When the point *e* has been reached the folding scroll is returned to its initial position and a like narrow fold is formed to the 25 point *f*.

When it is desired to form a wide fold *w* such as is used about the sleeves and bottom of the undershirt, which fold in the present instance is substantially four times the 30 width of the narrow fold about the neck, and at which time the undershirt is in tubular form, the folding scroll and folding tongue are adjusted to the positions shown in Fig. 3, with the latches 20 and 21 engaging the notches 20^b and 21^b, respectively.

To permit the completion of a fold on tubular work the folding tongue is withdrawn to the position shown in dotted lines, Fig. 3, thereby affording a clear and unobstructed 40 passage between the folding scroll and the edge-guide through which the initially stitched part of the fold is free to pass.

Having thus set forth the nature of the invention, what I claim herein is—

45 1. An attachment for sewing machines including in combination a base-plate, an edge-guide provided with a supporting shank secured to said base-plate, an open-sided folding scroll adjustably secured to said base-plate and facing said edge-guide, an adjustably mounted folding tongue which projects into said folding scroll, and means for maintaining said adjustable parts in operative position and permitting the withdrawal of the folding tongue from within 50 said folding scroll to permit the completion of a fold on tubular work.

2. An attachment for sewing machines including in combination a base-plate, an 60 edge-guide secured thereto, an open-sided folding scroll adjustably supported at one side of the line of seam formation and a folding tongue cooperating with said fold-

ing scroll, said folding tongue being adjustably supported at the opposite side of the 65 line of seam formation and projecting thereacross and into the folding scroll, said folding scroll and folding tongue being so constructed and arranged as to permit their retraction in opposite directions to afford a 70 clear and unobstructed passage therebetween to permit the completion of a fold on tubular work.

3. An attachment for sewing machines comprising a base-plate, an edge-guide supported thereby, folding means including an open-sided folding scroll facing said edge-guide and supported by said base-plate, said folding means and edge-guide acting respectively to produce a fold on a piece of fabric 80 and guide the inturned edge thereof, said folding scroll being so constructed and arranged as to permit of its retraction from said edge-guide to permit the edge-guide to guide the edge of an unfolded fabric. 85

4. An attachment for sewing machines comprising a base-plate, an edge-guide supported thereby, an open-sided folding scroll adjustably supported on said base-plate and facing said edge-guide, a folding tongue 90 overlying said edge-guide and projecting into said folding scroll, said edge-guide, folding scroll and folding tongue each cooperating with the others to produce a fold of predetermined width, said folding scroll 95 and folding tongue also being so adjustably supported and arranged as to permit their retraction in opposite directions to uncover the edge-guide and expose the same to permit it to guide the edge of an unfolded 100 fabric.

5. An attachment for sewing machines comprising a base-plate, an edge-guide, a folding scroll and a folding tongue each adjustable relative to said edge-guide, and spring latches adapted to engage and hold 105 said scroll and tongue in adjusted positions, said latches being secured to the under side of the base-plate and having portions accessible from above the base-plate for reTRACTING said latches.

6. An attachment for sewing machines comprising a base-plate, an edge-guide, a folding scroll and a folding tongue each provided with a plurality of notches and adjustable relative to said edge-guide, and spring-latches cooperating with said notches to hold said scroll and tongue in adjusted 115 positions, said latches being secured to the under side of the base-plate and having portions accessible from above the base-plate for releasing said latches from said notches. 120

In testimony whereof, I have signed my name to this specification.

ALBERT H. DE VOE.
